UNITED STATES PATENT OFFICE.

WILLIAM F. HENDRY, OF OSSINING, NEW YORK, ASSIGNOR TO MANHATTAN ELECTRICAL SUPPLY COMPANY, INCORPORATED, OF NEW YORK, N. Y., A CORPORATION OF MASSACHUSETTS.

ELECTRICAL ATTACHMENT DEVICE.

Application filed January 7, 1924. Serial No. 684,785.

This invention relates to improvements in electrical attachment devices, and more particularly to an improved base for attachment plugs.

5 The object of this invention is the provision of a base for attachment plugs which is of simple and sturdy construction, which may be readily assembled without the necessity of using screws or rivets, without the 10 necessity of soldering joints therein, and which is firmly held in its assembled condition without danger of the contact-making elements becoming loosened.

With this object in view, the present invention contemplates the provision of a single means for holding together the base including a contact shell and two contact springs. The single means consists of a wire of suitable size which serves as a 20 clamp for the whole structure. This is accomplished by knotting, bending, or otherwise rendering one end of the wire too large for being pulled out of a recessed portion of an insulating body. The other end of 25 the wire is spiralled into a contact-making surface and acts also as the other jaw of the clamp.

Obviously, the invention is capable of various embodiments and applications without departing from the spirit thereof, and the present specification is merely a detailed description of a preferred embodiment.

In the drawings, Fig. 1 is a side elevation of the base;

35 Fig. 2 is a vertical cross section of the base and a side elevation of a cooperating cap;

Fig. 3 is a view of one end of the base;

40 Fig. 4 is a view of the other end of the base;

Fig. 5 illustrates the wire serving as a clamp for the base assembly; and

Fig. 6 is a vertical cross section along lines 6—6 of Fig. 3.

45 1 is a body of insulating material provided with a knurled projecting rim 2 by means of which it may be grasped, and with three longitudinal passageways 3, 4, 5 projecting therethrough. The passageways 3 and 5 are large enough to receive contacts 6 and 7, respectively, of the cap 8, adapted to engage resilient contact springs 9 and 10 provided within said passageways. A disc 55 of insulating material 11 is provided on top of the body 1. The disc is perforated at 12 and 13, said perforations registering with the passageways 4 and 5, respectively. The upper end of the body 1 is surrounded by a contact-making surface or shell 14, screw-threaded to cooperate with a lamp socket or the like. The shell 14 terminates in a flange 15 bearing against the upper end of the body 1. The upper end of the contact spring 9 is turned down into contact with the flange 15 of the shell 14 and is held in that position by the disc 11 bearing against it. The upper end of the contact spring 10 projects through the perforation 13 in the disc 11 and its end is turned at substantially 60 90°, terminating in an ear 16 through which 65 a resilient wire 17 may project.

Normally, the wire 17 is in the condition shown in full lines in Fig. 5, that is to say, in the form of a straight rod having its end spiralled into a spring of a few convolutions.

70 The base is assembled by placing the contact shell 14 over the end of the body 1, then inserting the contact spring 9, then positioning the disc 11 through the opening 75 13 of which the spring 10 is inserted into the passageway 5. The wire 17 is now inserted through the perforation in the ear 16 of spring 10, the perforation 12 in the disc 11 and the passageway 4, the end of the 80 spring reaching practically down to the end of the passageway 4.

85 By means of suitable tools the lower or free end of the wire 17 is bent up into a half loop 18 against a recessed portion 19 of the passageway 4, whereby it can no more be pulled out through the passageway 4. Instead of bending up the wire 17 in the manner herein illustrated, it may be otherwise spread out or knotted to prevent its withdrawal. The 90 other end of the wire is flattened out into a spiral 20, all the convolutions of which are in one plane. All the elements of the base will be rigidly held within the clamp formed by the wire 17, which clamp is relatively resilient and resists shaking and other strains better than screws or rivets. The 95 end 20 of the wire serves to make contact with a lamp socket or the like. If a light gauge wire is used for this purpose and it 100 is desired further to remove the contact-

making surface 20 from the shell 14 without increasing the width of disc 11, an additional small disc may be inserted just below a spiral 20. The curling of the upper end of wire 17 may be accomplished as a single operation during the assembly of the shell.

It will be seen, therefore, that the continuous piece of wire 17 constitutes a single unitary clamp by means of which the elements of the base are held in a mechanically and electrically assembled condition, and the use of screws, rivets, soldering, etc., is obviated. The wire 17 may be produced in large quantities by means of automatic machinery, and the absence of screws, nuts, rivets and the like in the assembly will materially speed up the assembly of the device.

What I claim is:

20 1. An electrical attachment device comprising a body of insulating material, two contact springs, and a contact-making surface; and a resilient clamp for holding all of said elements in a mechanically and electrically assembled condition.

25 2. An electrical attachment device comprising a body of insulating material, two contact springs and a contact making surface; and a wire passing through said body and bent at its two ends to constitute a resilient clamp for all of said elements and also to constitute a second contact making surface.

30 3. An electrical attachment plug comprising an insulating body having three longitudinal passages, a contact-making surface partially surrounding said body, a disc of insulating material, two perforations in said disc registering with two of said passages, 35 a wire projecting through one of said passages and the corresponding perforation in the disc, having one of its ends held against removal from said passage and the other end bent to clamp said disc, contact springs in the two other passages, the end of one of said springs being clamped against said contact making surface by said disc, and the end of the other spring projecting through the other perforation of said disc and being

clamped to the latter by the bent end of said wire.

4. An electrical attachment plug, an insulating body having three longitudinal passages, a contact shell partially surrounding said body and provided with a flange bearing against the end thereof, a disc of insulating material positioned on top of said flange, two perforations in said disc registering with two of said passages, a wire projecting through one of said passages and the corresponding perforation in the disc, having one of its ends held to prevent its removal from the passage and the other end curled against the top of said disc, contact springs in the two other passages, the end of one of said springs being clamped between the body, the shell and the disc, and the end of the other spring projecting through the other perforation of said disc and being clamped to the latter by the curled end of said wire. 70

5. An electrical attachment plug consisting of an insulating body having three longitudinal passages the central one of which is provided with an offset portion, a screw-threaded contact shell partially surrounding said body and provided with a flange bearing against the end thereof, a disc of insulating material of substantially the same diameter as said body positioned on top of said flange, two perforations in said disc registering with the central and one of the other passages, a resilient wire projecting through the central passage and the corresponding perforation in the disc, having one of its ends bent against the recessed portion to prevent its slipping and the other end pressed in spirals against the top of said disc to form a contact-making surface, contact springs in the two other passages, the end of one of said springs being clamped between the body, the shell and the disc, and the end of the other spring projecting through the other perforation of said disc and being clamped to the latter by the spiralled end of said wire. 85

In witness whereof, I hereunto subscribe my name this 4th day of January, 1924.

WILLIAM F. HENDRY.
